TONE CONTROL SYSTEM

Poul F. G. Holst, Audubon, N. J., assignor to
 Radio Corporation of America, a corporation of
 Delaware

Application May 31, 1935, Serial No. 24,245

17 Claims. (Cl. 250—20)

The present invention relates to tone control systems for radio receiving systems and has, for its primary object, to provide an improved tone control system which may provide audio frequency compensation in predetermined relation to changes in selectivity of the high frequency circuits, to provide a predetermined frequency response in the system.

It is a further object of the present invention to provide tone compensating means in a plurality of audio frequency amplifier circuits and in one or more high frequency amplifier circuits of a radio receiving system, the high frequency amplifier control means being arranged to vary the selectivity of the receiving system, and the audio frequency control means being arranged to vary or adjust the audio frequency response characteristic, in cooperative relation to the first named control means, whereby the over-all fidelity of the receiving system may be controlled in a predetermined manner.

It is also an object of the present invention to provide uni-control adjustment of the audio frequency output characteristic of a radio receiving system by simultaneous adjustment of tone compensating networks in one or more audio frequency stages and selectivity control elements associated with the high frequency signal circuit.

The invention further relates specifically to multi-range radio receiving systems having wave band selector means whereby the receiver is responsive to radio signals in a plurality of differing wave bands, and has, for its further object, to provide means connected with the wave band selector means for the uni-control adjustment of the audio frequency response characteristic of the system, and the selectivity characteristic in predetermined mutual relation, whereby a predetermined over-all response characteristic is obtained for each differing wave band.

Further, in accordance with the invention, in addition to the tone control system comprising simultaneously adjustable uni-control high frequency and low frequency circuits, whereby the selectivity and audio frequency response are adjustable by common means in predetermined mutual relationship, separate and independent filters, manual tone and volume control means are interposed in the radio receiving system preferably between the high receiving circuits and the audio frequency amplifier circuits and, accordingly, it is a further object of the present invention to provide independent manual tone and volume control means and the like in a radio signal receiving system between the high frequency

and low frequency circuits comprising the adjustable tone control system, as hereinbefore referred to.

The invention will, however, be better understood from the following description when considered in connection with the accompanying drawings, and its scope will be pointed out in the appended claims.

In the drawings, Figure 1 is a schematic circuit diagram of a superheterodyne radio receiving system embodying the invention, and

Figs. 2 and 3 are graphs or curves illustrating certain audio frequency response characteristics of the system in Fig. 1.

Referring to Fig. 1, a radio receiving system of the superheterodyne type is provided with adjustable selectivity control means in a plurality of high frequency receiving circuits such, for example, as the intermediate frequency amplifier circuits. The latter circuits are illustrated in the figure in connection with the usual higher frequency receiving means indicated in the block enclosure 5. The receiving means is indicated as being provided with a wave band selector means for five different wave bands designated by the letters X, A, B, C and D, having a movable control element 7.

The receiver is supplied with radio signals from any suitable source, such as antenna and ground means 9, and produces an intermediate frequency signal in the output leads indicated at 11. The output leads are coupled to the first intermediate frequency amplifier tube 13 through tuned transformer coupling means adapted to provide adjustment selectively and comprising a primary winding 15 connected with the intermediate frequency output leads 11, and two secondary windings inductively coupled therewith as indicated at 17 and 19. The secondary windings 17 and 19 are connected in series and a variable tuning capacitor 21, connected with the high potential side of the circuit and the secondary winding 17 at 23, may be connected through a lead 25 selectively with the secondary winding 17 or both windings in series through a five point selector switch 27 and leads 29 and 31, the latter being connected at a point between the series connected secondary windings. The tap switch points are designated with the same reference letters as the corresponding wave band adjustment points indicated on the receiving system in connection with the selector means 7, and it will be seen that, when the selector switch 27 is adjusted in connection with the points X and A, the two secondary windings are in series with the

tuning capacitor 21. Connected in shunt therewith, a resistor 33 of low resistance value is inserted in circuit to be included in series with the winding 19.

5 When the switch is adjusted for the points B, C and D, the condenser is connected directly across the winding 17 which is the main secondary winding.

10 In a radio receiver, as shown herein, the frequency response of the system is adjusted in the higher frequency bands as the adjusting means is moved from the X band toward the D band. For the purpose of more clearly understanding the operation of the system, the operating bands for a receiving system, such as that

- 15 shown, is as follows:
20	Band X=140-410 kilocycles
	Band A=540-1800 kilocycles
	Band B=1800-5600 kilocycles
	Band C=5600-18000 kilocycles
	Band D=18000-60000 kilocycles

25 The secondary winding 19 provides additional coupling with the primary winding 15 and, together with the resistor 33, which may be approximately of 75 ohms, the receiving circuit for the first intermediate frequency amplifier may have a normal selectivity characteristic for the bands X and A, corresponding, in band A, to the present broadcast band. For the short wave bands B, C and D, they have an improved selectivity characteristic.

30 The tube 13 is thus the first intermediate frequency amplifier tube and is supplied with grid biasing potential on the control grid indicated at 35 through a filter resistor 37, which may be connected with any suitable source of biasing potential (not shown). For this purpose, the resistor 37 is connected with the lead 25 so that 40 the connection is made in any case to the low potential side of the tuned circuit.

35 Sensitivity control for the radio receiving system is provided in connection with any suitable circuit and, in the present example, is connected 45 with the first intermediate frequency amplifier tube as a variable bias control resistor 39 in series with the fixed self-bias potential resistor 41 in the cathode circuit indicated at 43. This represents any suitable separate manually controllable 50 sensitivity control means in connection with the receiving system, preferably in connection with the high frequency amplifying portion thereof.

55 The first intermediate frequency amplifier tube 13 is coupled through a suitable untuned inter- 60 stage transformer 45 with a second intermediate frequency amplifier tube indicated at 47. The output coupling means for the tube 47 comprises a transformer 49 and tuned secondary circuit, comprising two windings 51 and 53, corresponding to 65 the windings 17 and 19 respectively, for the preceding stage, and a tuning condenser 55 controlled in a similar manner by a selector switch 57 having a corresponding number of selector points similarly designated. The selector point, correspond- 70 ing to band X, alone is connected through a lead 59 and a resistor 61 with the secondary windings 53 and 51 in series. While all of the other connection points for the broadcast and higher frequency bands, the secondary alone is connected in shunt with the tuning condenser. With this arrangement, the tuned circuit is broader only on the X band and is sharper on all of the other bands. Whereas, in the preceding stage, the tuning is broader on both the X and A bands and is

sharper only on the higher frequency bands B, C and D.

5 The switches 57 and 27 are connected for uni-control operation with the wave band switch 7, as indicated by the dotted line connection 63, and a suitable control knob for simultaneous operation of all switches is indicated at 65. This may be considered as the wave band, selectivity, and tone control knob and in operation may be associated with the sensitivity control knob or operating device for the sensitivity control device 10 39, the said control knob being indicated at 67.

10 With the sensitivity control means shown, the transition to provide increased selectivity in the higher frequency bands is made progressively 15 from the signal input end of the receiver toward the detector, which is indicated at 69, and comprises diode and triode amplifier elements having a common cathode 71. The diode element is provided by a pair of diode anodes 73 connected with 20 the tuned circuit by a suitable tap 75 on the inductance 51, the cathode 71 being connected through a cathode lead 75 and a diode circuit impedance 77 with the switch 51, and thence to the low potential side of the tuned circuit either 25 in connection with the auxiliary secondary 53 through the lead 59, or through the main secondary winding 51 by way of contacts A to D inclusive, and a lead 79 connected at a point between the series connected windings. The diode recti- 30 fier provides the second detector for the receiver shown, and direct current biasing potential and the audio frequency component of the rectified signal is taken from the diode circuit impedance or resistor 77 through a lead 81, forming the connection between the condenser and the switch 57 35 and a grid lead 83 connected with a control grid 85 associated with the cathode 71. An anode 87 provides, with the grid 85 and the cathode 71, a triode amplifier for audio frequency signals which 40 are transmitted through suitable filter elements 89 and 91 and through a suitable coupling condenser 93 to manual tone and volume control means indicated by the rectangular enclosure 95.

45 The anode current is supplied to the device 69 through a filter impedance 97 and a coupling choke coil 99, this type of coupling system being common and well known. The tone and volume control means 95 is independent of the wave band selector and selectivity adjusting means and is 50 provided with separately adjustable volume and tone control means for manual operation, such as control knobs 101 and 103, respectively.

55 The controlled audio frequency signal output from the means 95 is conveyed to a suitable multi-stage audio frequency amplifier through an output lead 105, the return connection for which is taken through a lead 107 being a common ground return circuit for the receiving system continuing through a lead 109 and a lead 111 to the volume 60 control means.

65 The leads 105 and 107, therefore, constitute output leads for the system to which the audio frequency amplifier is connected and, in the present example, such amplifier comprises an input trans- 70 former 113 having the low potential end 115 of a primary winding 117 connected with the lead 107 and ground, while the high potential end 119 of the primary winding is connected through a tapped inductance 121 with the contacts A, B, C and D of a selector switch 123. The contacts B, C and D correspond to the similarly designated contacts of the selectivity control switches and band change means and are connected with the output end terminal 125 of the series choke 75

coil or inductance 121, while the contact A is connected to a tap 127 thereon intermediate its ends.

A contact X for said switch is connected through a lead 129 with a tap 134 on the secondary 135 of the transformer which is in turn connected with a pair of electric discharge amplifier devices or tubes 133 in balanced relation, whereby the control grid 137 of one of the push-pull amplifier tubes is connected with the lead 131 and

one end terminal of the transformer secondary 135, while the control grid 139 of the other tube is connected to the opposite high potential side of the input circuit or lead 141, in turn, connected with the opposite terminal 143 of the transformer secondary 135. A center tap 145 is connected through a self-bias resistor 147 with the cathodes 149 of the tube 133 and is also connected through a lead 151 with the ground lead 107.

The inductance 121, which in some steps is connected in series with the primary winding and serves to resonate with the distributed secondary capacitance of the transformer together with the lumped capacitance connected across the secondary by the switch, thereby producing a low-pass filter where the audio cut-off is preceded by a response peak, caused by the lack of loading in the secondary. This peak may be used to compensate for attenuation of the higher audio frequencies by the high frequency amplifier.

The height of the peaks is regulated by the resistances connected in parallel with the condenser loads as in the steps C and D, for example.

The balanced or push-pull first stage amplifier is coupled to a pair of output amplifier electric discharge devices 151 through a push-pull or balanced interstage transformer 153, providing a balanced input circuit for the tubes 151 having input leads 155 and 157 connected with the control grids 159 and 161 respectively, while the center tap 163 for the secondary 165 is connected with a suitable source of biasing potential indicated by the lead 167.

The output tubes 151 are coupled in balanced relation through a suitable push-pull or balanced output transformer 169 with an audio frequency output circuit 171 which may be connected to any suitable output device such as a loud speaker 173.

For the purpose of so controlling the signal output, the audio frequency amplifier is provided with tone compensating means preferably in a plurality of stages, such as the first and second stages shown, and such compensating means may, with greatest simplicity and at low cost, be provided by loading the secondaries of each of the input transformers for the succeeding stages, although other suitable tone control means may be used to provide a plurality of differing frequency response characteristics in accordance with changes in selectivity.

In the present example, in the first stage, a condenser resistance loading means is provided across the input circuit in connection with the input leads 131 and 141, under control of a tap switch 175 having tap points designated the same as and

corresponding to those for the preceding switches. This switch is connected through a lead 177 with one side 141 of the input circuit while the tap points are connected successively through loading means such as condensers 179, 181, 183 and 185 through the tap points A, B, C and D, respectively, connected in parallel on the opposite side through a lead 187, in turn connected through the lead 129 with the opposite side of the input circuit 131. The condensers 183 and 185 for the points C and D are each provided with a parallel

connected resistor 189 and 191, respectively.

The second or output stage input circuit is similarly loaded under control of a switch 193 having a connection 195 with one side 157 of the input circuit and having contacts X, A, B, C and D similar to the first named switch through the contacts A, B, C and D of which it is connected through loading condensers 197 having a common connection lead 199 with the opposite side 155 of the input circuit. It will be noted that the contact X, corresponding to the X wave band of each switch 175 and 193 are open circuited, while the contact X of the switch 123 is connected through the lead 129 with one side of the input circuit of the first stage amplifier.

With this arrangement, the output circuit of the detector 105 is connected directly through one half of the secondary winding 135 in the input circuit of the first stage amplifier, the return to the detector being through the lead 151 and the common lead 107. The secondary of the first audio frequency input transformer thus becomes an auto-transformer for more closely coupling the detector or audio frequency input circuit with the initial audio frequency amplifier stage.

The switches 123, 175 and 193 are interconnected as indicated by the dotted line 201 for simultaneous uni-control operation successively through the five positions of adjustment of the switches, the switches being in corresponding positions throughout and as shown being in contact each with the terminal X, as is also each selectivity control switch 27 and 57 and the wave band adjustment means 7.

The audio frequency compensation control 35 switches are further mechanically connected with the control means 7 and the switches 27 and 57, as indicated by the dotted connection 203 whereby audio frequency compensation and selectivity changes are made simultaneously by common 40 control means 65. The connection is such that the wave band changes may be made independently of the tone and selectivity changes as represented by the coupling 202 which may be released and under this condition the selectivity 45 and tone control is effected by an auxiliary control knob 204. In certain receiving systems the coupling 202 may be omitted.

It will be noted that the first tone control switch 123 provides direct coupling with the 50 secondary of the audio frequency input transformer 113 through a selected tap 134. This results in a wider response at the high end of the audio frequency range than would be possible with the same transformer used conventionally.

The succeeding tone control changes are arranged to include the series inductance 121 in the primary circuit either in part or wholly to resonate as hereinbefore described.

The tone control may be arranged other than as shown in each stage to provide any desired characteristic in predetermined relation to the selectivity.

For example in a facsimile receiver it may be 65 desired to decrease the selectivity and increase the width of the audio response in the high end of the audio frequency band, on the radio wave band, when the facsimile signals are received.

The resulting response characteristics provided 70 by the control system shown, are indicated in Fig. 2 by five curves, each letter corresponding to the tap switch point for which it represents the output characteristic of the audio frequency amplifier. The curves are plotted, as indicated, 75

between frequencies in cycles per second and the audio signal response or amplitude resulting from constant input.

From the curves, it will be seen that with the type coupling directly with the secondary of the input transformer and without loading, the amplifier is designed to have a substantially flat and extended frequency response in the upper end of the audio frequency range. In this position of the switch corresponding to position X, it will be seen that the selectivity of the high frequency amplifier is made broader by the inclusion in circuit of two secondary windings providing additional coupling means and by the use of series resistance in the intermediate frequency amplifier.

For the position A, the second high or intermediate frequency circuit is caused to be more selective and the input circuit of the audio frequency amplifier is, accordingly, tuned by the inclusion of a portion of the inductance in the primary winding and secondary loading or tuning means in each of the audio frequency amplifier stages.

The resulting increased amplitude in the region of 5,000 cycles, as shown by the curve A, serves to compensate for the reduction in the high frequency response of the receiver, normally resulting from increasing the selectivity whereby the response characteristic remains substantially flat at the output circuit. Likewise, for the band B, with increased selectivity resulting from operation of the switch 27, the primary winding receives signals through a larger inductance comprising the entire choke coil or inductance 121, while the secondaries in each stage are more heavily loaded by condensers or other suitable means connected with the point B of the switches 175 and 193.

It has been found, however, for the higher frequency receiving bands, it is desirable to reduce the high frequency response, and this is accomplished by further loading both audio frequency stages by both condenser and resistance loads in the first stage through the contacts C and D, and by additional condenser loads in the second stage through corresponding contacts C and D. The curves C and D in Fig. 2 indicate the resulting response characteristic obtainable by the means shown.

The system shown has the further advantage that a stepped tone control system both in the high frequency and low frequency circuits is provided to operate simultaneously and in predetermined mutual relation to the wave band being received to provide uniform frequency response up to the high frequency end of the audio frequency range to the limit which has been found practical in use without receiving undesirable interference.

For the reception of signals in one frequency band, it may be desirable to extend the high frequency range as indicated in Fig. 2 by the curve X and to extend the high frequency response as far as possible in each of the other higher frequency ranges of signal reception, but with the additional characteristic that each of the frequency response ranges are sharply cut-off at the predetermined limit of the range to be obtained for that wave band.

Accordingly, the wave bands or frequency response bands are adjusted by suitable control means and the resulting change in selectivity effected by the means provided is not only suitably compensated to provide a uniform audio frequency response from the audio frequency

amplifier, but the adjustment of the tone characteristic of the audio frequency amplifier is further changed in mutual relationship thereto to provide the stepped sharp cut-off points with increased frequency response.

It should be noted that in each step the frequency characteristic may be controlled independently of the frequency characteristic in the other steps since separate means are provided in connection with each of the switches, thereby providing the possibility for compensating for variations in fidelity in the signals received at the manual tone and volume control means and derived therefrom to the output circuit 105 of Fig. 1.

Since a different degree of compensation for tone or fidelity and a different degree of selectivity is desirable in predetermined mutual relationship for each frequency band to be covered by the multi-range radio receiver, each of the control means for the selectivity and tone should have a corresponding number of positions to be provided by the wave band selector means.

In any case, however, in accordance with the invention, the audio frequency response range of the receiver is increased by switching the input connection to the audio frequency amplifier from the secondary or audio transformer connection to the primary or regular transformer connection including series inductance for raising the response characteristic at the high frequency range with sharp cut-off.

Furthermore, there is thus available in a radio receiver, arranged in accordance with the invention, a plurality of output frequency characteristics, each being shaped to compensate for the selectivity in a predetermined desired relationship, and an improved and effective control of the frequency characteristic is obtained by the combination of controls in a plurality of stages and including the input circuit to the amplifier in conjunction with the primary winding for the higher frequency wave bands.

It will be noted that the sensitivity control means 39 is provided with independent manual operating means such as a control knob 67.

Under certain conditions or for the reception of certain types of signals the sensitivity may best be changed in predetermined mutual relationship with the selectivity in the same manner as the wave band change or the tone change. Hence, any suitable connection may be made to operate the sensitivity control means, as by a mechanical connection indicated by the dotted connection line 206, having a releasable coupling 208, whereby independent operation is possible. In the present example the connection is open for operation of the knob 67 manually and independently.

Referring to Fig. 3, curves X₁, A₁, B₁, C₁ and D₁ correspond to the curves similarly lettered in Fig. 2 and indicate the over-all response characteristic of the amplifier of Fig. 1, in conjunction with the selectivity control means.

The dotted curves X₂, A₂, and the dotted curve B₂ C₂ D₂ indicate the response obtainable without the compensation and the sharp cut-off filter included in the control system of Fig. 1 for the selectivity adjustments X, A and B—C—D of the switches 27 and 51 alone. It will be seen that higher frequency noises and undesired signals would be amplified ordinarily beyond the desired range of cut-off for each step in the adjustment of the tone control feature and the response would not be extended to the limit in each step as indicated by the solid line curves. With the

control arrangement shown, therefore, the result in output is adjustable in steps which extend the audio frequency range or reduce it as desired to predetermined limits, as the selectivity is adjusted and may also include simultaneous wave band change. The selectivity and tone control means are connected for uni-control operation, and the changes may be effected in desired predetermined mutual relationship also with wave band change to produce the result in output as indicated by Fig. 3.

I claim as my invention:

1. In a radio receiving system adjustable for response to signals in a plurality of frequency ranges, the combination with means for providing said adjustment, means for tuning said system through each of said frequency ranges, means connected with said first named means for uni-control operation therewith simultaneously to adjust the selectivity of said system, an audio frequency amplifier, and means for adjusting the frequency response characteristic of said audio frequency amplifier in predetermined relationship to changes in frequency range of operation of said system, said last named means being connected with said first named means for conjoint uni-control operation therewith, whereby a differing degree of selectivity and a differing audio frequency response characteristic is provided in accordance with and for each differing frequency range of operation of said system.

2. In a multi-range radio receiving system, wave band selector means, high frequency amplifier means, low frequency amplifier means, and means connected with the wave band selector means for uni-control operation therewith simultaneously to adjust the selectivity of the high frequency amplifier means and the frequency response characteristic of the low frequency amplifier means in predetermined mutual relationship.

3. In a multi-range radio receiving system, wave band selector means, high frequency amplifier means, audio frequency amplifier means, and means connected with the wave band selector means for uni-control operation therewith simultaneously to adjust the selectivity of the high frequency amplifier means and the frequency response characteristic of the audio frequency amplifier means in predetermined mutual relationship, said audio frequency amplifier means comprising a plurality of electric discharge amplifier stages, a transformer having a primary winding and a secondary winding providing an input coupling means for said audio frequency amplifier, and said frequency response control means comprising a selector switch for connecting the audio frequency input signals directly to the secondary of said transformer to provide an auto-transformer and alternatively to the primary winding, and a series inductance for said primary winding included in circuit therewith for said first named control means.

4. In a multi-range radio receiving system, the combination with means for changing the tuning range of said system, a high frequency amplifier including a plurality of electric discharge amplifier devices and interstage coupling means therefor providing a series of tunable circuits, of an audio frequency amplifier including a plurality of stages, for receiving rectified signals through said first named amplifier, and means for varying the selectivity of said tunable circuits and the response characteristic of a plurality of said audio frequency amplifier stages in predetermined mu-

tual relationship with change in tuning range of the system.

5. In a multi-range radio receiving system having wave band selector means, the combination with a high frequency amplifier including a plurality of electric discharge amplifier devices and interstage coupling means therefor providing a series of tunable circuits, and an audio frequency amplifier for receiving rectified signals through said first named amplifier, of means for varying the selectivity of said tunable circuits and the response characteristic of a plurality of said audio frequency amplifier stages in predetermined mutual relationship, said wave band selector means comprising a movable element having a plurality of selected positions of adjustment, and said selectivity and audio frequency response control means comprising selector switch elements having a number of positions of adjustment corresponding to the wave band selector means and connected therewith for uni-control operation, and means in circuit with said switch elements providing a plurality of differing selectivity and audio frequency tone control characteristics for said system, whereby a uniform predetermined over-all fidelity characteristic is obtained.

6. In a multi-range radio receiving system, having wave band selector means, the combination with a high frequency amplifier including a plurality of electric discharge amplifier devices and interstage coupling means therefor providing a series of tunable circuits, and an audio frequency amplifier for receiving rectified signals through said first named amplifier, of means for varying the selectivity of said tunable circuits and the response characteristic of a plurality of said audio frequency amplifier stages in predetermined mutual relationship, said wave band selector means comprising a movable element having a plurality of selected positions of adjustment, and said selectivity and audio frequency response control means comprising selector switch elements having a number of positions of adjustment corresponding to the wave band selector means and connected therewith for uni-control operation, and thereby a uniform predetermined over-all fidelity characteristic is obtained.

7. A radio receiving system in accordance with claim 6, further characterized by the fact that the audio frequency response control system includes means in the audio frequency amplifier providing a plurality of sharp high frequency cut-off points corresponding to the several positions of wave band selector means.

8. In a radio receiving system having a high frequency signal amplifier, a detector and a low frequency rectified signal amplifier, the combination with the high frequency signal amplifier of selectivity control means and wave band selector means, means for changing the response characteristic of the low frequency amplifier simultaneously with the selectivity and wave band changes under uni-control, whereby a stepped tone control system is provided, and means for providing sharp cut-off points in the low frequency response characteristic at the higher frequency end thereof with changes in adjustment of said wave band selector means.

9. In a radio receiving system, means for adjusting the frequency response of said system in a plurality of differing bands, an intermediate frequency amplifier having selectivity control means comprising a tunable signal circuit, a switch in said circuit for varying the selectivity and having positions corresponding to the posi-

tions of adjustment of the wave band selector means, a second detector connected between said intermediate frequency amplifier and a plurality of electric discharge amplifier stages, providing 5 an audio frequency amplifier, said amplifier having an input transformer provided with a primary winding and a secondary winding, an inductance in circuit with said primary winding for tuning said winding, switch means for connecting said 10 output circuit selectively with a tap on the secondary winding of said transformer and to said primary winding including said inductance, selective switching means and condenser load means connected therewith for shunt connection across 15 the input circuits of at least two of the stages of said audio frequency amplifier, said switches having positions of adjustment corresponding to the positions of adjustment of said wave band selector means and being connected therewith 20 and with said selectivity control switch for simultaneous uni-control operation.

10. In a radio receiving system for wave band selector means, a high frequency amplifier and a low frequency amplifier, each comprising a plurality 25 of cascade connected stages, of selector means for progressively increasing the selectivity of the high frequency stages with increase in the frequency of the selected wave bands, selector means for progressively loading the signal transmission circuits of the audio frequency amplifier simultaneously with increase in frequency of the selected wave band, selector means for changing the audio input circuit from auto-transformer to transformer coupling with increase in frequency 30 range of the selected wave band, means interconnecting said selector means for uni-control operation, whereby the wave band change high frequency and audio frequency adjustments are effected thereby in predetermined mutual relationship. 35

11. The combination with a multi-range radio receiving system having wave band selector means whereby the receiver is responsive to radio signals in a plurality of differing wave bands, means 45 connected with and actuated by said selector means for adjusting the audio frequency response characteristic of the system, and uni-control means for adjusting the selectivity characteristic of the system in predetermined mutual relation with the audio frequency response characteristic. 50

12. The combination with a multi-range radio receiving system having wave band selector means whereby the receiver is responsive to radio signals in a plurality of differing wave bands, means 55 for adjusting the audio frequency response characteristic of the system, and uni-control means for adjusting the selectivity characteristic of the system in predetermined mutual relation with the audio frequency response characteristic, said uni-control means being connected with the wave band selector means whereby a predetermined over-all fidelity response characteristic is obtained for each differing wave band. 60

13. In a radio receiving system, the combination 65 with wave band changing means, of signal

amplifier means, means for modifying the frequency response characteristic of one signal amplifier thereby to modify the audio frequency output characteristic of the system, means for modifying the frequency response characteristic 5 of another of said amplifiers thereby to modify the audio frequency response characteristic of the system in a differing degree, and means providing uni-control operation of said wave band changing means and modifying means, whereby 10 the response characteristics are varied in predetermined mutual relation in two differing amplifier circuits with wave band change.

14. In a radio receiving system, the combination with wave band changing means, of a high 15 frequency amplifier, a signal detector following said high frequency amplifier and an audio frequency amplifier following said detector in the signal channel of said receiver, uni-control means for simultaneously adjusting the first named 20 means, the selectivity characteristic of the high frequency amplifier and the audio frequency response characteristic of the audio frequency amplifier, sensitivity control means for said system, and means for connecting said last 25 named control means with said first named and second named means for uni-control operation therewith, and means for independently varying the volume and tone characteristic of said system. 30

15. A radio receiving system in accordance with claim 14 characterized by the fact that it is provided with wave band changing means whereby it is responsive to signals in a plurality of differing wave bands, and further characterized by the 35 fact that adjustment of the wave band means is arranged to operate said uni-control means in predetermined relation to the wave band adjustment.

16. In a radio receiving system having a high 40 frequency amplifier and an audio frequency amplifier including a plurality of stages, the combination with wave band selector means, of means for adjusting the selectivity of the system in two differing high frequency amplifier stages, means 45 for adjusting the audio frequency response characteristic in at least two audio frequency amplifier stages, said wave band selector and selectivity and audio frequency response adjusting means being inter-connected and jointly controllable, 50 and the selectivity being adjustable in one amplifier stage prior to adjustment in another amplifier stage.

17. A radio receiving system in accordance with claim 16, further characterized by the fact that 55 changes in selectivity are accompanied by predetermined change in audio frequency characteristic, and the coupling in at least one audio frequency amplifier stage being provided directly through an audio frequency transformer when the selectivity is lowest and indirectly through a coupling transformer having a tuning inductance in series with the primary thereof when the selectivity is increased to a predetermined point. 60

POUL F. G. HOLST. 65
